United States Patent Office

Des. 217,997
Patented July 7, 1970

217,997

COMB

Samuel H. Bundles, Jr., and Henry M. Childrey, Indianapolis, Ind., assignors to Summit Laboratories Inc., a corporation of Indiana

Filed Apr. 4, 1969, Ser. No. 16,584

Term of patent 14 years

Int. Cl. D28—03
U.S. Cl. D86—8

FIG. 1

FIG. 2

FIG. 3

FIG. 1 is a top perspective view of a comb showing my new design;

FIG. 2 is a top plan view thereof with the other side being of substantially the same configuration; and

FIG. 3 is an end view thereof with the other end being of substantially the same configuration.

We claim:

The ornamental design for a comb, substantially as shown and described.
